Related U.S. Appl. No. 62/580,289, filed Nov. 1, 2017 entitled "Systems for Winch Rope Interfaces and Recovery Rigging Mountable to a Winch Fairlead and/or Vehicle Bumper".

Primary Examiner — Cynthia R Underwood

(74) Attorney, Agent, or Firm — K&L Gates LLP

(57) **CLAIM**

The ornamental design for rope link, as shown and described.

DESCRIPTION

FIG. 1 illustrates a perspective view of a rope link embodying the invention.

FIG. 2 illustrates a front view of the rope link shown in FIG. 1.

FIG. 3 illustrates a rear view of the rope link shown in FIG. 1.

FIG. 4 illustrates a left side view of the rope link shown in FIG. 1.

FIG. 5 illustrates a right side view of the rope link shown in FIG. 1.

FIG. 6 illustrates a top view of the rope link shown in FIG. 1; and,

FIG. 7 illustrates a bottom view of the rope link shown in FIG. 1.

1 Claim, 6 Drawing Sheets(56)
